UNITED STATES PATENT OFFICE.

JOHN R. RHOADS, OF BOYERTOWN, PENNSYLVANIA.

AUTOMOBILE HEADLIGHT WRENCH.

Application filed November 1, 1924. Serial No. 747,285.

This invention relates to wrenches, and more particularly to a wrench designed for use in connection with the head-lights or lamps of motor vehicles, and an object of 5 the invention is to provide a wrench as specified, which is readily adjustable to fit the metal rings of various sized lamps, to permit the ring to be removed or replaced on the lamp and which will not in any way 10 mar or mutilate the rings or lamp structures with which it is used.

A further object of the invention is to provide a wrench as specified, which includes a pair of handles, cooperating with semi- 15 circular spring plates which by means of the handles, may be quickly moved into proper gripping engagement with the vehicle lamp, the said two handles permitting a greater leverage to be exerted upon the 20 lamp ring, if necessary.

Other objects of the invention will appear in the following detail description and in the accompanying drawings wherein:—

Figure 1 is a plan view of the wrench 25 showing it in open position.

Figure 2 is a plan view of the wrench showing it in closed position with parts in section.

Figure 3 is a side elevation of the wrench.

Figure 4 is a detail section through the 30 wrench.

Referring more particularly to the drawings, the improved wrench comprises a pair of body members 1 and 2, which are semi-circular in shape and are constructed of 35 spring steel or analogous material. Each of the body members 1 and 2 has one of its ends extended and doubled back upon itself to provide a hinge barrel 3 through which 40 a hinge pintle 4 extends. The barrel 3 is provided with a cut-out portion intermediate its ends through which the flattened portion of the levers 5 extends. The levers 5, one of which is provided at each side of the 45 wrench, is pivotally connected to one of the sections by means of the pintle 4 and to the other section by means of a hinge pintle 6 which extends through a hinge barrel 7, which has a slot 7a. A hinge barrel 7 is 50 attached to the outer surface of the body member a short distance inwardly from its

free end. The manner of connecting the levers 5 (which includes apertures 5a) to the members 1 and 2 will permit the body members 1 and 2 to be moved so that their ends will overlap as clearly shown in Figure 2 of the drawings when the levers are moved into wrench clamping positions, so as to provide a firm and solid grip upon the vehicle lamp to be operated on. The lining 10 of any suitable type of fabric is attached in any suitable manner to the inner surfaces of the sections 1 and 2, so as to prevent marring or mutilation of the vehicle lamp on which the wrench is used.

In use, the handles 5 are moved tangentially from the main body of the wrench, as shown in Figure 1 of the drawings, at which the maximum inner diameter of the wrench is had. The wrench is then placed over the removal ring of the head-light and the levers are moved on their pivots to collapse the wrench or reduce its inner diameter and bring it into firm gripping engagement with the lamp ring. Continued application of 75 power or pressure to the handles to remove the wrench in a rotary manner to either unscrew the ring from or screw it upon the lamp.

It is, of course, to be understood, that the 80 invention may be constructed in various other manners and the parts associated in different relations, and therefore, I do not desire to be limited in any manner, except as set forth in the claim hereunto appended. 85

What I claim is:—

A device of the class described comprising a pair of semi-circular band members, each one of said members having one of its ends folded upon itself to form a hinge 90 barrel, a separately formed hinge barrel operatively fastened to each one of the semi-circular members adjacent the free ends thereof, one of said hinge barrels having a U-shaped slot, a pair of operating levers, 95 one end of one lever being flattened to fit in said U-shaped slots, said flattened end being provided with a pair of apertures for pivotally connecting said levers to said hinge barrels.

In testimony whereof I affix my signature.
JOHN R. RHOADS.
